CHAIN ATTACHMENT

Alexis W. Lemmon, Upper Arlington, Ohio, assignor to The Jeffrey Manufacturing Company, a corporation of Ohio

Application October 6, 1943, Serial No. 505,178

10 Claims. (Cl. 198—175)

This invention relates to a chain attachment or to a chain having an attachment which reinforces the side bar of the chain link.

An object of the invention is to provide a chain attachment or a chain having an attachment which so reinforces a side bar of a chain link as to increase its effective life and to reduce appreciably the danger of breakage thereof.

Another object of the invention is to provide a chain attachment constructed to prevent breakage of the chain under the influence of a load carried thereby.

Other objects of the invention will appear hereinafter, the novel features and combinations being set forth in the appended claims.

In the accompanying drawing,

Fig. 1 is a plan view showing a conveyor chain mechanism and bucket type flights including the features of my invention; and

Fig. 2 is a sectional view through one of the flight buckets showing one of the chains of Fig. 1 in side elevation.

Referring to the drawing, the conveyor mechanism illustrated includes a pair of spaced pintle chains 10 formed of pivotally connected links 11 and attachment links 12, the attachment links 12 and links 11 being pivotally connected by removable pins 13. The attachment links 12 perform the functions of links 11 and in addition support a bucket type flight 14, the buckets 14 being connected between link attachments 12 on the two spaced chains 10. In the conveyor section illustrated, one bucket is omitted.

It has been found in practice that the usual attachments are such that should one chain lead the other by a slight amount, there is a tendency for the inner side bar to break adjacent its base or next to the thimble of the attachment to which it is integrally formed, since the entire attachment is cast as a single member.

The feature of my invention is to provide a construction which prevents this breakage when one of the chains 10 leads the other or, in other words, when one of the chains 10 tends to take more of the load than the other. To this end each of the attachments 12 is formed by a pair of spaced side bars 15, 16 which are formed as an integral part of a cross member constituting a knuckle or barrel 17. In fact the entire attachment 12 is preferably formed as an integral steel casting. Extending inwardly from each attachment link 12 and forming an integral part thereof and specifically formed integrally with the inner side bar 16 thereof is a web 18 to which an

attaching plate 19 is integrally formed on its innermost edge. The two sides of the bucket flight 14 are preferably attached to opposite attachment plates 19 by means of bolts or rivets

5 20. To prevent breaking of the side bar 16 adjacent the knuckle 17, in case one of the chains 10 tends to assume all of the load or get ahead of the other chain, I provide reinforcing means in the form of an integral supporting arm or ear 21 which extends rearwardly from the web 18 and is spaced inwardly from the side bar 16 and is also an integral part of the link attachment 12.

The rearmost portion of the arm or ear 21 is provided with a generally cylindrical head 22 which has a central bore aligned with the bore in the knuckle or barrel 17, through which two aligned bores an elongated pivot and attaching pin 23 extends and is removably held in place by any desired means such as a cotter key extending through a radial hole in the end thereof. The opposite end of the pin 23 is preferably provided with an integral head.

In the operation of the conveyor mechanism it is evident that the load will be carried by any 25 attachment link 12 not only through the side bars 15 and 16 but also through the arm or ear 21 and be transferred by the knuckle 17 and the head 22 to the pivot pin 23 which pivotally connects said attaching link to the succeeding chain link 11. As a consequence of this structure should one of the chains 10 lead the other and thus place a bending load on the side bar 16, because of the presence of the flight 14, said side bar 16 will be reinforced and the bending and possible breakage of the side bar 16 which might otherwise take place will be prevented because of the force transmitted through the arm or ear 21 to the pin 23. In other words, the arm or ear 21 will reinforce the side bar 16 and effectively free it from the breaking, twisting force which might otherwise result from the condition above mentioned.

It is to be noted that this result is accomplished without in any way altering the structure between the side bars 15 and 16 and this portion of the link attachment acts substantially in the same way as the ordinary link 11 and is free to receive the tooth of the driving sprocket which drives each chain 10.

It may be further pointed out that when the conveyor is assembled, the knuckle 17 and the two side bars 15 of the attachment link 12 are between the leading ends of the side bars of the original link 11. Furthermore, the inner side bar of the

ordinary link 11 is between the side bar 16 and the reinforcing arm 21 and the pin 23 extends through aligned bores or pin holes in the reinforcing arm 21, the two side bars of the ordinary link 11, the two side bars 15 and 16 of the attachment link 12 and the knuckle 17 thereof.

Considering the forces on the inside bar only on the ordinary link 11, it is to be noted that these forces are distributed to the attachment link 12 by way of the pin 23 through the head 22 of the reinforcing arm 21 and through the inner side bar 16 and knuckle 17.

It is to be further noted that while the reinforcing arm 21 is rigidly connected to the side bar 16 by means of the web 18, the rear portion thereof including the head 22 is spaced inwardly from said side bar 16 and knuckle 17 to accommodate the head end of the inner side bar of the ordinary link 11 which is pivotally connected between them by pin 23.

It is also to be noted that each of the attachment links 12 has three longitudinal extending, integrally connected, spaced apart, force transmitting members in the two side bars 15 and 16 and the arm 21.

The aligned holes in knuckle 17 and head 22 may also be considered as three aligned holes through the two side bars 15 and 16 and head 22.

Obviously those skilled in the art may make various changes in the details and arrangement of parts without departing from the spirit and scope of the invention as defined by the claims hereto appended, and I therefore wish not to be restricted to the precise construction herein disclosed.

Having thus described and shown an embodiment of my invention, what I desire to secure by Letters Patent of the United States is:

1. A chain including pivoted links and attachment links, at least one of said attachment links having an integral reinforcing arm spaced from a side bar of said attachment link, and pivot pins connecting said links and attachment links and extending through aligned holes in said attachment links and said reinforcing arm.

2. A chain attachment link including regular chain side bars, and an integral reinforcing arm spaced therefrom and attached thereto, and aligned pivot pin receiving bores in said regular link and reinforcing arm.

3. A chain including a link having side bars and an integral knuckle, an attachment link having side bars and an integral knuckle, a flight attachment member attached to one of the side bars of said attachment link, a reinforcing arm attached to one of the side bars of said attachment link, said reinforcing arm and the attach-

ment link knuckle having aligned bores, and a connecting pin extending through said bores and through a bore in said link and said attachment link.

4. A chain including a link having side bars, an attachment link having side bars and an integral knuckle, a flight attachment member attached to one of the side bars of said attachment link, a reinforcing arm attached to one of the side bars of said attachment link, said reinforcing arm and the attachment link knuckle having aligned bores, and a connecting pin extending through said bores and through a bore in said link and interconnecting said link and said attachment link.

5. A chain including a link having side bars and an integral knuckle, an attachment link having side bars, a flight attachment member attached to one of the side bars of said attachment link, a reinforcing arm attached to one of the side bars of said attachment link, said reinforcing arm and the attachment link having aligned bores, and a connecting pin extending through said bores and through a bore in said link and interconnecting said link and said attachment link.

6. A chain including a link having side bars, an attachment link having side bars, a flight attachment member attached to one of the side bars of said attachment link, a reinforcing arm attached to one of the side bars of said attachment link, said reinforcing arm and the attachment link having aligned bores, and a connecting pin extending through said bores and through a bore in said link and interconnecting said link and said attachment link.

7. An attachment link including a side bar, a flight attaching member connected to said side bar, a reinforcing arm attached to said side bar, said arm and link having aligned pin receiving bores.

8. In combination, a chain link and an attachment link, said attachment link having a spaced reinforcing arm, said link having a side bar extending between said attachment link and said reinforcing arm, and a connecting pin extending through aligned holes in said link, reinforcing arm and attachment link.

9. An attachment link, including spaced side bars and an integral knuckle, and an integral attaching device having an integral reinforcing arm provided with a pivot pin receiving hole.

10. An attachment link having three longitudinally extending integrally formed force transmitting members having aligned connecting pin holes therein, two of said members being connected by an integral knuckle having a pin hole aligned with those aforesaid.

ALEXIS W. LEMMON.
